UNITED STATES PATENT OFFICE.

MAX WALBRECHT, OF WEST HOBOKEN, NEW JERSEY, ASSIGNOR TO COLLINS & AIKMAN COMPANY, OF JERSEY CITY, NEW JERSEY, A CORPORATION OF NEW JERSEY.

DESIGN FOR A TEXTILE FABRIC.

49,531.

Specification for Design.

Patented Aug. 15, 1916.

Application filed June 9, 1916. Serial No. 102,774. Term of patent 7 years.

To all whom it may concern:

Be it known that I, MAX WALBRECHT, a citizen of the United States, residing at West Hoboken, in the county of Hudson and State of New Jersey, have invented a new, original, and ornamental Design for Textile Fabrics, of which the following is a specification, reference being had to

the accompanying drawing, forming part thereof.

The figure is a view of a section of textile fabric, showing my new design.

I claim:

The ornamental design for a textile fabric, as shown.

MAX WALBRECHT.
